COMBINED PIPE CASE AND TOBACCO
POUCH

Arthur Dubsky, Jackson Heights, N. Y.

Application August 27, 1943, Serial No. 500,297

1 Claim. (Cl. 206—38)

This invention relates to a tobacco pouch made of a flexible and foldable material, such as for instance leather, which is fastened by means of a closing flap. The object of this invention is to combine such a tobacco pouch with a pipe case. The essential feature of this invention is that both the front and the back wall of the pouch are suitably extended so as to form a folding pouch and that the foldable extensions thereof are devised so as to form a pipe case, which is composed of a casing for the pipe bowl and a sheath for the pipe stem, thus combining the tobacco pouch with a pipe case in a manner that the two receptacles can be shut from each other by the fold common to both. According to the invention the arrangement is so that when the tobacco pouch is open, i. e. when the extensions of the two walls of the tobacco pouch, which form the closing flap, are unfolded, the pipe case, devised in between these extensions of the two walls of the pouch, that lie upon each other, is also open. At the pipe case filling opening the two walls are loosely lapped on each other in convenient length, i. e. a length corresponding to the filling opening of the pouch.

It is thus a characteristic feature of this combination of a tobacco pouch and a pipe case that the tobacco pouch and the pipe case have a common filling opening through which, when the fastening flaps are opened, both receptacles are accessible, i. e. the pouch may then be filled with tobacco and the pipe may be placed into, or taken out of, the pipe case.

By this invention the pipe case is formed by the foldable extensions of the front and back walls of the tobacco pouch so that, when the latter is closed by way of folding, the case for the pipe bowl will not lie upon the pouch; i. e. the bowl case and the tobacco pouch will not lie upon each other, but that, instead, the bowl case will be situated beside the tobacco pouch. Such a device serves the purpose that, notwithstanding the combination of the tobacco pouch with a pipe case, the tobacco pouch, when filled, will not become bulky on account of the pipe. For the same purpose the invention also provides that the portion of the pipe case that forms the sheath for the stem and/or mouthpiece is arranged just so far above the fold that when the tobacco pouch is folded up the pipe stem will lie just below the fold of the pouch, i. e. on the thinnest part of the filled and folded pouch. So the pipe stem does not cause bulkiness of the filled pouch either. By placing the sheath for the pipe stem opposite the pipe bowl case adjacent to the filling opening a supporting layer is formed for the pipe stem so

that its falling out of the pipe case is prevented.

A combined tobacco pouch and pipe case of such kind may be readily devised so that the portion of the pipe case meant as a receptacle for the pipe bowl is widened, for instance by the provision of a gusset, so as to be suitable for casing the pipe bowl. This pipe bowl case is lapping over the tobacco pouch and will prevent the tobacco from running out of the pouch in this place, i. e. where the bowl case is, even if the folding flaps are open. Such a device will easily permit the pocket-like cavity for the pipe bowl to be used as a supporting layer between tobacco and pipe bowl, which, in turn, will allow the pipe bowl to be filled within the case, while the tobacco pouch is open, without need of a tobacco filler and without need to use one's fingers, in short, without any expedient whatsoever.

Another characteristic feature of the tobacco pouch that is the object of this invention is the combination of two receptacles of different sizes, of which the larger one, viz. the tobacco pouch, is fastened by a fold, whereas the other receptacle, viz. the pipe case, which the same fold shuts off from the tobacco pouch, is open and accessible from outside and/or from within the filling opening, a device that is meant to prevent the tobacco from taking the unpleasant smell of the used pipe.

The drawing shows an embodiment of a tobacco pouch combined with a pipe case in accordance with the invention. Fig. 1 gives a front view of the tobacco pouch in closed position, Fig. 2 in open position; Fig. 3 shows a cross section taken on line B, B of Fig. 2; Fig. 4 gives a plan view of Fig. 2; Fig. 5 shows a cross section taken on line A, A of Fig. 1; Fig. 6 is a side view of Fig. 1 in the direction of the arrow C; and Fig. 7 shows a cross section taken on line A, A while the tobacco pouch is filled with tobacco. The two walls of the tobacco pouch in the drawing, i. e. front 1 and back 2 are extended beyond the fold 3 (see Figs. 1 and 2) so as to form a folding pouch of which the said extensions together constitute the closing flap, and which by means of folding, or bending, of these extensions of the walls in the fold is thus fastened in, or by, this fold. By means of a snap fastener 4 the extensions of the two walls, which together form the closing flap, may be kept folded and closed. It is between the two folding extensions of the walls that a pipe case is devised consisting of a case 5 for the pipe bowl and a sheath 6 for the pipe stem. The arrangement is so that the pipe case 5, 6, formed in between the extensions of the walls, will be

accessible from the filling opening 1 of the opened tobacco pouch where the two side parts, of a length corresponding to the width of the filling opening, are loosely lapping on each other. Thus, both the tobacco pouch 8 and the pipe case 5, 6 are accessible through the filling opening when the tobacco pouch is open, in such a position permitting tobacco to be filled into the pouch and the pipe to be placed into, or to be taken out of, the pipe case. As shown in the drawing (Figs. 3 and 4), part of the pipe case 5, 6 is widened, for instance by the provision of a gusset 10, forming a case 5 wide enough for the pipe bowl; this pipe bowl case is so arranged that when the tobacco pouch is closed or folded it does not lie upon the pouch 8 but beside, i. e. outside the latter. This serves the purpose that when the tobacco pouch is filled it will not increase in bulk due to the pipe lying thereon, as shown in Fig. 7. To further serve this purpose the pipe case is also so arranged that when the tobacco pouch is open it appears just as far above the fold 3 as to allow the pipe stem to lie just below the fold when the pouch is closed by folding. This place will be the thinnest part of the filled and closed tobacco pouch (as shown in Fig. 7) so that the pipe stem will not cause bulkiness of the filled tobacco pouch either.

The drawing shows that, when the pouch is open, the pipe bowl case 5 flaps over the tobacco pouch 8 so that the running out of tobacco from the pouch, while open, will be prevented in this place. The pipe bowl case 5 will thus also serve as a supporting layer both for the pipe bowl and between the latter and the tobacco and allow the bowl to be filled without any expedient within the tobacco pouch.

By way of joining the extensions of the tobacco pouch opposite the pipe bowl case 5 and adjacent

to the filling opening 1 a supporting layer 9 for the pipe stem is formed, which will support the pipe stem lying exposed between the folding extensions of the sides and prevent its falling out of the pipe case.

With such an arrangement when the tobacco pouch is closed and its sides are folded up the pipe bowl case 5 will find itself beside said tobacco pouch and the latter may have, notwithstanding its combination with the pipe case, a filling opening of convenient size, and no, or only an unimportant, reduction of the width of this filling opening with regard to the width of the tobacco pouch 8 will be required.

In the drawing only the outer wall 2 of the extension of the tobacco pouch, which is somewhat longer than the inner side, has been used for the snap fastening device 4.

I claim:

20 A combined tobacco and pipe pouch formed of flexible leather comprising spaced front and rear walls and a bottom wall forming a pouch for holding tobacco, integral upward extensions on said front and rear walls forming prolongations of said front and rear walls, said upward extensions 25 extending laterally and upwardly and having their edges closed forming a lateral offset pocket, said extending walls and pocket forming an upper pipe pouch for holding a pipe with the bowl in said pocket, the material between the tobacco pouch and the pipe pouch being foldable whereby the pipe pouch is adapted to be folded over the tobacco pouch in intimate contact therewith with the pipe bowl pocket offset laterally from the tobacco pouch and forming an elongation thereof when the parts are in folded position.

ARTHUR DUBSKY.
